International Search Report for AU 20049033567, filed Jun. 29, 2004.

International Search Report; dated Feb. 11, 2005; International Application No. PCT/AU 2004/001672. First Examination Report; dated Feb. 15, 2005; Australian Innovation Patent No. 2004101018.

Primary Examiner—Doris Clark(74) *Attorney, Agent, or Firm*—Gardere Wynne Sewell LLP(57) **CLAIM**

The ornamental design for a trim systems component for building structures, as shown and described.

DESCRIPTION

FIG. 1 is a perspective view of the trim systems component for building structures of the present design; FIG. 2 is a front view thereof; and,

FIG. 3 is a right side view thereof.

The trim systems component for building structures has been broken on the end indicating indefinite length. The bottom of the trim systems component for building structures is flat and devoid of ornamentation. The left side of the design is identical to the right side.
